Filed Apr. 8, 1968, Ser. No. 11,353

Term of patent 14 years

U.S. Cl. D23—148
Int. Cl. D23—04; D28—03

FIG. 1 is a perspective view of the facial vaporizer embodying my new design;
FIG. 2 is a top plan view;
FIG. 3 is a side elevation;
FIG. 4 is a view from the left in FIG. 2; and
FIG. 5 is a bottom plan view.

The dominant features of my design reside in the portions shown in full lines.

For convenience of illustration the hose and face mask are omitted in FIGS. 2 through 5.

I claim:
The ornamental design for a facial vaporizer, as shown and described.
